MAGNETIC AND FLUID REGULATION OF ELECTRIC CURRENT

Filed Nov. 19, 1920

Charles H. Snoot

INVENTOR.

UNITED STATES PATENT OFFICE.

CHARLES H. SMOOT, OF NEW YORK, N. Y., ASSIGNOR TO RATEAU BATTU SMOOT ENGINEERING CORPORATION, OF NEW YORK, N. Y., A CORPORATION OF DELAWARE.

MAGNETIC AND FLUID REGULATION OF ELECTRIC CURRENT.

Application filed November 19, 1920. Serial No. 425,092.

To all whom it may concern:

Be it known that I, CHARLES H. SMOOT, a citizen of the United States, residing at New York, 110 West 71st Street, have invented certain new and useful Improvements in Magnetic and Fluid Regulation of Electric Current, of which the following is a specification.

This invention relates to the regulation of electric current. I have devised means through which I correlate the pressures of a flow of fluid (gas or liquid) to the changes of electromagnetic forces derived from the electric current I wish to regulate.

15 The correlation between fluid pressures and electromagnetic forces is brought about by means of a variable size orifice interposed in the path of the fluid and controlled as to its size by the electromagnetic forces.

20 The means I employ to carry out my invention are a plurality of solenoids, or the like, some moving, some stationary, in which electromagnetic force is generated in proportion to the current passing through the 25 various windings. The current passing through the various windings being the current I wish to regulate. The relative position of the solenoids varies the position of a valve which controls the size of the variable 30 opening I interpose in the flow of fluid.

The contraction of the orifice raises the fluid pressure and the enlargement of the orifice allows for a fall of fluid pressure.

The rise and fall of the fluid pressures are 35 the agencies through which I operate a rheostat, or the like, which in turn controls the electric current I wish to regulate.

To those skilled in the art it will be plain that I have devised means whereby speeds 40 of driving apparatus, strength of field coils, etc., may be adjusted to maintain a given delivered result in power, current, voltage, etc., regulated in a predetermined manner.

45 Referring to the drawing, the figure is a vertical, sectional view of an embodiment of my invention, in which I have used conventional electrical symbols.

As illustrated, the figure shows the means I have devised to maintain a constant potential between the leads of an alternator.

50 Alternator A has a direct current field B, its leads being C and D. E is a direct current exciter, with shunt field coil F, driven by engine G.

Solenoids 1 and 3 are stationary; 2 is a movable solenoid.

The connections between solenoids 1, 2 and 3 are such that a downward magnetic force is created, tending to pull the movable solenoid 2 downwards with a force increasing with an increasing potential between alternator leads C and D. This downward magnetic force, as well as the weight of solenoid 2 and connected parts, is counterpoised by the adjustable weight 6. Attached to the beam arm 4 is a stem 8 and the upper end of spring 7 the lower end of the spring being secured to the piston 9 of the dash pot 10. The rod 8 to which the spring 7 is secured passes freely through the piston of dash pot 10 which may be filled with oil. By-pass 32 is controlled by screw 31 in such a way that the resistance of oil passing from one side to the other of piston 9 is made adjustable. Dashpot 10 is affixed to stem 11, which in turn is affixed to the moving piston 12 operating in cylinder 14. 15 is a bent rod arm fulcrumed on lever 4 and terminating in a valve 16, riding under the orifice 17. 18 is a pipe supplying fluid under pressure to operating cylinder 14.

Fluid enters the operating cylinder 14 through strainer 19 and exerts its pressure in the annular chamber 20, after passing through port 33. 21 is a needle type by-pass valve controlling the orifice area of port 22, whereby a restricted amount of fluid under pressure is admitted into the space 23 above piston 12. This operating fluid escapes from the cylinder through orifice 17, its quantity being controlled by valve 16. 24 is a stuffing box preventing the escape of fluid under pressure from annular chamber 20. 25 is a connecting rod, articulated to piston 12 and to lever 26 of rheostat 27. The terminals of the rheostat 27 are connected by conductors 28 and 29 to the shunt field F and exciter E. Solenoids 1 and 3 are stationary, while solenoid 2 is affixed to beam arm 4, which is fulcrumed by flexible member 30 to a point of support 5.

The operation of the illustrated embodiment of my invention, described above, is as follows:

Adjustable weight 6 is made to counterpoise the magnetic force developed between solenoids 2 and 1, and 2 and 3, for the desired potential between leads C and D of

alternator A, and when so adjusted lever 4 is in equilibrium and holds valve 16 slightly away from orifice 17, allowing the escape of fluid from chamber 23 at the same rate as it enters the port 22. If for any reason the potential between leads C and D is reduced, the downward effort exerted by solenoid 2 is reduced and the solenoid moves upward, carrying with it lever 4, arm 15 and valve 16, which upward motion restricts the escape of fluid through orifice 17, resulting in an accumulation of fluid in chamber 23, and downward motion is communicated to piston 12 by the increasing pressure in chamber 23. This downward motion of piston 12 operates the rheostat 27, moving the lever 26 downward, and reduces the resistance in the field circuit of exciter E, whereby a greater potential is generated and the excitation of field B of alternator A is increased sufficiently to restore the potential between alternator leads C and D to its original value. However, the potential at C, D does not immediately respond to the change in the rheostat and due to this lag there is liable to be set up beats, the lever 26 oscillating up and down in a periodic manner. To overcome this tendency to beats, I introduce the resilient member 7 between the lever 4 and the piston 12. The resilient member 7 allows a certain amount of overtravel of the rheostat are to temporarily compensate for the delay in the correction of the potential variation at C, D. For example, a rise in the potential at C, D will cause a downward movement of coil 2. This will compress the spring 7 and open the valve 16 quicker and to a greater extent than if there were no resilient member, whereupon the piston 12 will move upward, the resistance 27 will be increased and excitation diminished quicker than it would otherwise, which results in a correction compensating for the lag and thus doing away with objectionable oscillations or beats.

As the potential of the alternator is restored to its normal value, the departure from normal of magnetic force on solenoid 2 is reduced and the action of spring 7 on lever 4, and thence on valve 16, causes piston 12 to return to normal position.

This action is complete for a very rapid change and restoration of potential, but for a slow change of potential the flow of oil around piston 9 gradually releases the tension in spring 7, which produces a correspondingly reduced effort upon lever 4 and a reduced action in restoring piston 12 to its original position, so that the piston and its connected rheostat lever takes up a new position, although the coil 2 and its lever 4 will have returned to the middle or balanced position.

It will thus be apparent that this combina-

tion of dashpot and spring compensates for the time delay between motion of control arm 26 in rheostat 27 and delay change in voltage between the leads C and D, due to the time necessary to increase the field current in the field winding B and alternator A.

The lag between the change in voltage and the corrective means is such as to counteract any tendency to "beats."

To those skilled in the art it is plain that solenoids 1, 2 and 3 may be interconnected to regulate for constant current, constant potential, or some other function.

In accordance with the provisions of the patent statutes, I have described the principle of operation of my invention, together with an embodiment of my invention, but I desire to have it understood that the apparatus shown is only an illustration and that the invention can be carried out by other means.

To those skilled in the art it will be shown that I have devised means to correlate the magnetic forces of solenoids 1, 2 and 3, which are in proportion to electrical quantities developed with the pressure of a fluid flowing through and controlled by a variable orifice comprised by valve 16 and orifice 17, which orifice is under the dependence of the magnetic forces.

On the one hand the magnetic forces are dependent on the electric current flowing from lead C and on the other hand rheostat 27 is operated by the pressure of the fluid in chamber 23.

The correlation I have created between the magnetic forces and the fluid pressures causes the interaction of the electric current to be regulated by the rheostat for its control.

The location of the rheostat in the electric system described is immaterial as regards the spirit of my invention and has been selected for an illustrative purpose only.

I claim:

1. Means for regulating electric current which comprises in combination, electromagnetic devices responsive to changes in the current and correlating fluid pressure devices controlling a flow of fluid, means responsive to said fluid pressure devices to vary the electric current to be controlled, and resilient means interposed between the electromagnetic devices and the fluid pressure responsive means, said resilient means being adapted to cause the fluid pressure responsive means to overtravel momentarily to correct tendency to beats.

2. Means for regulating electric current which comprises in combination, electromagnetic devices responsive to changes in the current and correlating fluid pressure devices controlling a flow of fluid, means responsive to said fluid pressure devices to

vary the electric current to be controlled, a
retarding device interposed between the
electromagnetic devices and the fluid pres-
sure responsive means, resilient means inter-
5 posed between the electromagnetic devices
and the fluid pressure responsive means, said
resilient means allowing the fluid pressure

responsive means to temporarily overtravel
to prevent the occurrence of beats when the
changes in current are temporary and the 10
retarding device allowing the fluid pressure
responsive means to assume a new position
when changes in current are prolonged.

C. H. SMOOT.
